(57) **CLAIM**

The ornamental design for a nose hair trimmer, as shown and described.

DESCRIPTION

FIG. 1 is a front, right and top perspective view of a nose hair trimmer, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an exploded perspective view of the nose hair trimmer shown in an open state.

The broken lines shown in the drawings illustrate portions of the nose hair trimmer that form no part of the claimed design.
